UNITED STATES PATENT OFFICE.

DORRIS F. HENDRICKS, OF RUSSELL, KENTUCKY.

RAILWAY-CAR JOURNAL BEARING.

Application filed March 6, 1923. Serial No. 623,168.

To all whom it may concern:

Be it known that I, DORRIS F. HENDRICKS, a citizen of the United States of America, and resident of Russell, in the county of 5 Greenup and State of Kentucky, have invented certain new and useful Improvements in Railway-Car Journal Bearings, of which the following is a specification.

This invention relates to railway car frames and journal bearings and particularly to novel means whereby roller bearings are held in spaced relation to each other and inoperative relation to an axle, the bearing box having novel means by which it is assembled with relation to the frame to have oscillatory motion transversely of the frame.

It is a further object of this invention to provide a bearing box having novel configuration adapted to seat in and engage one 10 end of a side frame of a truck in order that there will be no lost motion between the box and side frame, due to thrust action, and in which a lateral movement of the box is allowed with respect to the side frame. The 15 last mentioned condition has been found advantageous in obviating fractures or injury to the side frame or bearing when derailment of the truck occurs, and permits a ready readjustment of the parts when re- 20 placed on a track.

It is a still further object of this invention to provide a bearing of the type described in which the journal and roller bearings are 25 geared together, and in which the roller bearings are geared to the box, the same being associated with a mounting that permits movement of the box laterally of the frame to compensate for any inequalities of the gage of the rails and other defects of the 30 roadbed, within predetermined bounds.

It is a still further object of this invention to provide novel means for attaching the box to the side frame to insure a durable construction while permitting the action heretofore indicated, the said device being of such 35 construction as to permit expeditious mounting or dismounting of the box.

With the foregoing and other objects in view, the invention consists in the details of construction, and in the arrangement and combination of parts to be hereinafter more 40 fully set forth and claimed.

In describing the invention in detail, reference will be had to the accompanying drawings forming part of this application wherein like characters denote correspond-

ing parts in the several views, and in which—

Figure 1 illustrates a view in elevation of a car truck embodying the invention;

Figure 2 illustrates a sectional view transversely of the frame with the journal in elevation on a larger scale than that of Fig. 1;

Figure 3 illustrates an enlarged sectional view of a fragment of the frame and transverse sectional view of the box and interior mechanism;

Figure 4 illustrates a perspective view of the box containing saddle;

Figure 5 illustrates a perspective view of a fragment of the frame;

Figure 6 illustrates a view in elevation of the journal bearing; and

Figure 7 illustrates a view in elevation of the roller bearing.

In these drawings 10 denotes the side frame of a truck, and the construction there-of between the boxes may be of any appropriate type and the inventor does not wish to be limited with respect to the shape of the side frame nor the manner in which it is 75 constructed or braced.

Each end of the side frame is of identical construction and the journal, boxes, and bearings at each end of the frame are of the same construction, and a description of the assembly at one end will suffice as a disclosure for an understanding of the invention by those skilled in the art.

It will be seen from an inspection particularly of Figs. 3 and 5 that there is a tubular extension 11 at the end of the frame and that this terminates in a downward and outward extension 12, the wall 13 of which preferably extends outwardly at an angle of the same degree as the angle of the wall 14, and these walls form a seat in which a sectional box 15 is held. The outer surfaces of the box are shaped to the contour of the walls 13 and 14 and the under surface of the tubular extension 11 making a close fit to obviate lost motion.

As stated, provision is made for retaining the roller bearings in spaced relation to each other within the box, and to that end the interior of the box is provided with two sets of teeth 16 and 17, the said sets of teeth being arranged circumferentially of the interior of the box and in spaced relation to each other and these sets of teeth are intended to engage sets of teeth 18 and 19, respectively, of the anti-friction rollers 20. The teeth 18

and 19 of the rollers also engage sets of teeth 21 and 22, respectively, formed on the journal 23, and when the journal and anti-friction rollers are assembled in the box, they 5 will be in the relations shown in Fig. 3.

The box is preferably sectional and the sections may be secured together by fastenings such as bolts 24.

The upper section of each box is preferably provided with sets of apertured ears 25 and 26, the ears of each set being in alignment and provided with rods, bolts or other fastenings 27 which are utilized for connecting the saddle 28 to the ears. The saddle 15 is of curved configuration and its inner surface is preferably of the same contour as the outer surface of the tubular extension 11 of the frame in order that the saddle will rock on the tubular extension. The upper surface 20 of the box is further provided with a convex seat 29 in which the lower surface of the tubular extension 11 is located. By the mounting just described, the box will have an oscillatory motion with respect to the extension of the frame with the resultant advantage heretofore indicated.

Any suitable closure 30 in the nature of a gate may be provided for opening or closing the entrance 31 to the interior of the box, 30 but the inventor does not wish to be limited with respect to these details.

The construction of the saddle is well

shown in Fig. 4, and the manner of mounting the saddle with relation to the ears on the box is well shown in Fig. 1.

35

It will be seen from an inspection of the drawing that a side frame made in accordance with this invention has a very graceful outline, and the fact that the extremities 12 embrace the sides of the boxes, the boxes are 40 held in their seats without the employment of strong anchoring means or devices that require unusual time for their adjustment.

40

I claim:

1. In a truck for railway cars, a side frame 45 having an extension with a rounded outer surface, a saddle thereon conforming to the contour of the said outer surface and oscillatable thereon, and a journal box under the extension of the frame to which the saddle is 50 connected.

2. In a car truck, a side frame having extensions at the ends with curved outer surfaces, a saddle on each extension conforming to the contour of the outer surface of the extension, a journal box seated under each extension of the side frame, and means for connecting the saddle to the said box.

55

3. In a truck for railway cars, a side frame having extensions, a saddle on each extension, a journal bearing box under the extension and means for connecting the saddle to the box on opposite sides of the frame.

DORRIS F. HENDRICKS.
